UNITED STATES PATENT OFFICE.

WALTER E. BARTHOLOMEW, OF NILES, MICHIGAN.

DESIGN FOR A TOY SADDLE HORSE.

60,974.

Specification for Design.

Patented May 23, 1922.

Application filed January 14, 1921. Serial No. 437,366. Term of patent 7 years.

To all whom it may concern:

Be it known that I, WALTER E. BARTHOLOMEW, a citizen of the United States, residing at Niles, in the county of Berrien and State of Michigan, have invented a new and original and ornamental Design for Toy Saddle Horses, of which the following is a specification, reference being had to the accompanying drawing, forming a part thereof.

The figure is a perspective view of a toy saddle horse showing my new design.

I claim:

The ornamental design for a toy saddle horse as shown.

In testimony whereof I have hereunto affixed my signature.

WALTER E. BARTHOLOMEW.
